Patented February 9, 1904.

UNITED STATES PATENT OFFICE.

FRANK J. REAVES, OF ROCKFORD, ILLINOIS, ASSIGNOR TO THE ROCKFORD WATCH COMPANY, LIMITED, A CORPORATION OF ILLINOIS.

DESIGN FOR A WATCH-WHEEL.

SPECIFICATION forming part of Design No. 36,778, dated February 9, 1904.

Application filed November 20, 1903. Serial No. 182,024. Term of patent 7 years.

To all whom it may concern:

Be it known that I, FRANK J. REAVES, a citizen of the United States, residing at Rockford, in the county of Winnebago and State of Illinois, have invented a new, original, and ornamental Design for Watch-Wheels, of which the following is a specification, reference being had to the accompanying drawing, forming a part hereof.

The figure of the drawing shows my design for watch-wheels.

What I claim as new, and desire to secure by Letters Patent, is—

The ornamental design for a watch-wheel, as herein shown.

FRANK J. REAVES.
